UNITED STATES PATENT OFFICE

TILLMAN CAHN, OF ELKINS PARK, PENNSYLVANIA, ASSIGNOR TO PIONEER SUSPENDER COMPANY, A CORPORATION OF PENNSYLVANIA

DESIGN FOR SUSPENDERS

Application filed January 6, 1932. Serial No. 42,379. Term of patent 14 years.

To all whom it may concern:

Be it known that I, TILLMAN CAHN, a citizen of the United States, residing at Elkins Park, in the county of Montgomery, State of Pennsylvania, have invented a new, original, and ornamental Design for Suspender, of which the following is a specification, reference being had to the accompanying drawing, forming part thereof.

The figure is a view in perspective of a suspender embodying the design.

The following comprises the distinguishing or characteristic features of the design: the three pads at the junction of the shoulder straps with the back strap are of radiating

foliate design. The pad at the lower end of the back strap is of foliate design similar to the two pads on the rear ends of the shoulder straps, all pointing upwardly; while the two pads at the front ends of the shoulder straps point downwardly and correspond in size and shape with the downwardly pointing pad at the top of the back strap. The three downwardly pointing pads carry the foliate suggestion, and all combine in presenting a harmony of foliations.

I claim:

The ornamental design for a suspender as shown and described.

TILLMAN CAHN.
